UNITED STATES PATENT OFFICE.

HERBERT E. KEELER, OF NEW YORK, N. Y., AND WILLIAM S. HAMM, OF CHICAGO, ILLINOIS, ASSIGNORS TO THE ADAMS & WESTLAKE COMPANY, OF ILLINOIS.

DESIGN FOR A LAMP.

SPECIFICATION forming part of Design No. 24,496, dated July 23, 1895.

Application filed June 21, 1895. Serial No. 553,612. Term of patent 14 years.

To all whom it may concern:

Be it known that we, HERBERT E. KEELER, residing in the city of New York, in the county and State of New York, and WILLIAM S. HAMM, residing at Chicago, in the county of Cook and State of Illinois, citizens of the United States, have invented and produced a new and original Design for Lamps, of which the following is a specification, reference being had to the accompanying drawing, which is a perspective view.

The upper portion A is substantially square in any horizontal plane and extends downwardly in four equal inwardly-inclined sides. It unites with a central portion B, constituting the lantern, of similar shape, but having a lesser angle of inclination than is given to the sides of the upper portion A. The central portion B is provided with panels *a* bounded by framework, while the upper portion A is ornamented by corner-pieces *b* and

edge-beading, as shown. Under and uniting with the said central portion B and in the vertical axis or line of it and the upper portion A is a third substantially cylindrical and ornamentally-beaded portion C, comprising the candle socket or holder. From the sides of the upper portion A extend pear-shaped bulbs D.

We claim—

The design for a lamp substantially as herein described and illustrated.

In testimony whereof we have hereto set our hands and seals.

HERBERT E. KEELER. [L. S.]
WILLIAM S. HAMM. [L. S.]

Witnesses for H. E. Keeler:
